UNITED STATES PATENT OFFICE.

STERLING ELLIOTT, OF BOSTON, MASSACHUSETTS.

GUARD FOR THIRD-RAIL SYSTEMS.

SPECIFICATION forming part of Letters Patent No. 703,563, dated July 1, 1902.

Application filed April 3, 1902. Serial No. 101,214. (No model.)

To all whom it may concern:

Be it known that I, STERLING ELLIOTT, a citizen of the United States, residing at Boston, Massachusetts, have invented certain new and useful Improvements in Guards for Third-Rail Systems, of which the following is a specification.

My invention relates to the electric conducting-rail of an elevated railway, commonly known as the "third rail;" and it consists of a guard designed to prevent the falling of sparks and in the form shown herein designed also to prevent accidental contact of persons with the said rail.

In the accompanying drawings I have shown a convenient, simple, and effective embodiment of my invention best known to me, these drawings showing in Figure 1 a portion of the guard in side elevation and in Fig. 2 a cross-section, all as hereinafter explained.

In the drawings, A represents the third or electric conducting-rail, which may be of the form shown in sectional Fig. 2. This rail has the usual support on an elevated track, which support and track need no illustration, being well known.

The object of my invention being to prevent the falling of sparks from the third rail upon persons or things below the track, I have considered it essential to that object to provide an inclosure which should confine such sparks within narrow lateral limits and which should cover the least possible floor-space on the track, and thus least obstruct the light. Further, it seemed desirable by the same structure to prevent accidental contact of persons with the rail and to accomplish these objects by simple and inexpensive means. I secure all these ends by means of

two guards of wood in the form of boards or planks, as shown at B. These being of non-conducting material may be made to rest directly upon the flange of the rail A, near or at the outer edge of the flange, so that the rail-flanges form the bottom of the spark-receiving space between the guard; but if guards be used of conducting material or of material of essentially greater conducting quality non-conducting strips may be interposed between them and the rail-flanges.

The position described brings the upper parts of the guard near to the sides of the head of

the third rail and in position to catch and deflect any sparks that may be formed on the passing of a car. These guards are coextensive with the rail. They are held in place and in relation to the rail by means of bolts 2, which pass through the web of the third rail and through both guards B, with proper washer 4 and nuts 3 to secure them in place. 55 Interposed between the web and the guards on each side are distance-pieces C, consisting of sleeves of wood or any suitable material placed on the bolts and bearing against the web at one end and the side of the guard at the 60 other, so that when the nuts are turned up the guards are fixed in place. As the guards are placed within the rail-base, no more of the limited space of the elevated road is occupied. The guards are extended above the 65 upper surface of the conducting-rail far enough to obstruct the sparks and at the same time to prevent accidental contact of persons, as aforesaid. The proportions as shown in Fig. 2 aforesaid are correct, but 70 may be varied without departure from the spirit of my invention. Sufficient elevation of the guards to arrest the sparks and sufficient space between rail-head and guard to permit them to fall into the larger spaces below the rail-head inclosed by the guard or the flanges must be provided. Small openings 75 may be made, if necessary, to permit the escape of water.

I claim—

1. In combination with the third or electrically-charged rail of an elevated railway, guards resting on the rail-flanges, and extending above the said rail and means for holding said guards in place, substantially as described.

2. In combination with the third or electrically-charged rail of an elevated railway, guards resting on the flanges of said rail and extending above the said rail, bolts, and distance-pieces securing said guards in place, all substantially as described.

In testimony whereof I affix my signature in presence of two witnesses.

STERLING ELLIOTT.
